US00D848433S

(12) **United States Design Patent** (10) Patent No.: **US D848,433 S**
Toyoda (45) Date of Patent: **** May 14, 2019**

(54) **MANAGEMENT CARD FOR DIGITAL SLIDES**

(71) Applicant: **HAMAMATSU PHOTONICS K.K.**,
Hamamatsu-shi, Shizuoka (JP)

(72) Inventor: **Yuichi Toyoda**, Hamamatsu (JP)

(73) Assignee: **HAMAMATSU PHOTONICS K.K.**,
Hamamatsu-shi, Shizuoka (JP)

(**) Term: **15 Years**

(21) Appl. No.: **29/621,868**

(22) Filed: **Oct. 12, 2017**

(30) **Foreign Application Priority Data**

Apr. 13, 2017 (JP) 2017-007958
Apr. 13, 2017 (JP) 2017-007959

(51) **LOC (11) Cl.** **14-02**

(52) **U.S. Cl.**

USPC **D14/436**; D14/435

(58) **Field of Classification Search**

2014/0144996 A1 *	5/2014 Friedman	G06K 19/06103 235/494	FIG. 8 is a front view of a second embodiment of the management card for digital slides of the present invention.				

FIG. 9 is a rear view thereof.

FIG. 10 is a top plan view thereof.

FIG. 11 is a bottom view thereof.

FIG. 12 is a right side view thereof.

FIG. 13 is a left side view thereof; and,
FIG. 14 is a reference view showing the management card
for digital slides in use.

The features shown in broken lines depict environmental
subject matter only and form no part of the claimed design.
The shades of grey represent a contrast in tone.
